CLAIM

The ornamental design for a housing for hand held data entry and display terminal, as shown and described.

DESCRIPTION

FIG. 1 is a front, top, left side perspective view of the housing for hand held data entry and display terminal showing our new design;

FIG. 2 is a left side elevational view thereof on an enlarged scale;

FIG. 3 is a rear elevational view thereof on an enlarged scale;

FIG. 4 is a bottom plan view thereof on an enlarged scale;

FIG. 5 is a right side elevational view thereof on an enlarged scale.

FIG. 1

FIG. 2

FIG. 3

FIG. 4

FIG. 5
